UNITED STATES PATENT OFFICE.

JAMES A. HERRICK, OF NEW YORK, N. Y.

GAS-PRODUCER APPARATUS.

1,005,210.

Specification of Letters Patent. Patented Oct. 10, 1911.

Original application filed March 26, 1909, Serial No. 485,992. Divided and this application filed July 15, 1909. Serial No. 507,723.

To all whom it may concern:

Be it known that I, JAMES A. HERRICK, residing at New York, in the county of New York and State of New York, have invented 5 certain new and useful Improvements in Gas-Producer Apparatus, of which the following is a specification.

This invention relates to gas producers and the present application, as to certain 10 features is a division of my application for gas producers, filed March 26, 1909, Serial No. 485,992.

One of the objects of the present invention is to provide new and improved means 15 for discharging fuel into the body of a producer and distributing it evenly upon the bed of fuel therein.

Another object is to provide improved 20 means for preventing the formation of crevices or fissures in the mass.

Other objects will be in part obvious and in part pointed out hereinafter.

The invention accordingly consists in the 25 features of construction, combinations of elements and arrangement of parts, which will be exemplified in the construction hereinafter described, and the scope of the application of which will be indicated in the following claims.

30 In the accompanying drawings wherein is illustrated a preferred form of embodiment of my invention: Figure 1 is a view in vertical section, of a producer constructed in accordance therewith; Fig. 2 is a similar view 35 of the upper portion of a producer showing a slightly different arrangement of certain of the component parts thereof.

Referring now to the drawings, 1 represents the base or setting of a producer, said 40 base being hollowed out as at 2, to provide an ash receptacle and container for the water employed to seal the lower end of the apparatus.

3 represents twyer boxes which distribute 45 the blast received from a bustle pipe 4; the latter receiving its supply from the blast pipe 5.

Any suitable means may be employed for 50 removing the ashes, such means in the present instance comprising Archimedean screws

7 which deliver ashes upon the traveling belt 8, which carries them from the producer.

The producer, which in the present instance is of cylindrical form is provided with a fixed upper section 10, and a fixed lower 55 section 11 between which is positioned a revolute section 12, which latter section is provided with wheels 13 adapted to traverse a supporting track 14 carried by the lower fixed section 11. Water seals as at 60 15 and 16 are provided between the fixed sections 10 and 11, and the revolute section 12, and the latter is encircled by a member 17, provided with peripheral gear teeth 18.

20 indicates a gear wheel, the teeth of 65 which mesh with teeth 18 of the member 17. Gear wheel 20 is carried upon the shaft 21. The upper end of which is provided with the bevel gear 21', with which meshes a bevel gear 24 mounted upon the driving shaft 22. 70

Upper fixed section 10 may be supported in any desirable manner, in the present instance pillars 25 and cross braces 26 performing this function.

Formed interiorly of the producer and 75 supported upon the inner walls of the revolute section 12 is an arched partition 27 having semi-circular apertures 28, which apertures form passage ways for the fuel and gases. In the present instance four of 80 these apertures are provided, said apertures being formed between the legs 30 which rest upon the inner wall of the revolute section 12. Partition 27 is provided with a central aperture 31 from which leads a conduit 32. This conduit is adapted for conducting gases from the producer and extends upward to the cover portion 33 and connects with a fixed discharge conduit 34 supported in any desirable manner above 90 the producer. Baffles as at 35 are provided in the conduit 32 which conduit is of such size as to constitute a mixing chamber for the outgoing gases.

The top portion or cover 33 of the producer is mounted to revolve upon the top section 10, being supported in the present instance by means of ball bearings 36. A water seal as at 37 is provided between the top section 10 and the cover portion, which 100

may be revolved by any suitable means as by means of the gear 38 upon the shaft 19. Shaft 19 is provided with a bevel gear 23, which meshes with the driving bevel gear 24. Shafts 19 and 21, it will be noted, abut intermediate the gears 21' and 23, so that they may be revolved in opposite directions, by means of the bevel gear wheel 24. This results in a revolution of the cover portion 16 in one direction, and the intermediate revoluble portion in the opposite direction.

The cover portion is provided with an aperture 40 through which extends a rotatable poker 41, the lower end of which is off-set 15 as shown. The poker is provided with a suitable apron 42 which dips into the water which covers the upper surface of the cover portion 33, and the edge of the cover portion is raised as at 43 so as to furnish a container 20 for the water. Poker 41 is hollow and a circulation of water is maintained therein by means of an open ended pipe 44 which extends through the same and terminates adjacent the lower end. Water is 25 charged into the poker through a hollow shaft 45 which in turn receives its supply from a pipe 46 leading from a trough 47. The water after passing downward through the poker and upward through pipe 44 is 30 discharged by pipe 48 upon the top of the cover portion. Shaft 45 is provided with a gear 50 which meshes with the peripheral teeth 51 formed upon the member 52 carried by the stationary discharge conduit 34. It 35 will be seen that when the cover portion 33 is rotated, the poker 41 will be moved bodily as well as independently rotated. The cover portion 33 is also provided with an aperture 53 through which extends a chute 54, said 40 chute depending into the interior of the producer. Leading into chute 54 is a hopper 55, said hopper and chute being provided with flanges 56 which rest upon an 45 standing portion 57 of the cover. Extending downwardly through hopper 55 is a shaft 58 provided with a plurality of laterally extending members 60 which are received between similar members 61 extending inwardly from the inner wall of the 50 hopper. This shaft carries an apertured plate 62, the apertures of which are adapted to register with apertures formed in the plate 63 carried by the hopper. It will be seen that when shaft 58 is revolved the 55 apertures of the plates 62 and 63 will be carried into and out of registry whereby fuel will be periodically discharged through the chute 54 into the producer. Shaft 58 is rotated as by means of a gear wheel 64 60 which meshes with the teeth formed upon the stationary gear 65 carried exteriorly of the fixed conduit 34. A funnel 66 may be employed for discharging fuel into the hopper through an aperture 67 in the cover 68,

which cover may be held stationary while 65 the hopper 55 is revolved. Any suitable means may be employed for supporting the funnel 66.

Having thus described the construction of this embodiment of my invention the operation may now be understood: The fuel which is introduced into the producer by means of the hopper 55 and chute 54 is evenly distributed upon the bed therein by the latter, owing to the fact that the same is 70 carried by the cover and rotates independently thereof; the poker 41 operating constantly to stir the mass and maintain the same free from crevices or fissures.

When the apparatus is in operation the 80 intermediate portion 12 is rotated as well as the cover portion, as has been above described. The blast which is received through an extension 70 passes downward through the mass to meet the gases passing upward 85 to meet the gases formed in the lower portion of the producer, and said gases mix in the conduit 32, prior to being discharged from the producer.

Referring to the embodiment of my invention illustrated in Fig. 2, the upper portion 71 of an up-draft producer is illustrated; the gases being carried off as by means of a discharge pipe 72. A hopper 73 and chute 74 deliver the fuel into the interior of the producer, apertured plates 75 and 76 being provided as in the embodiment above described. The apertured plate 75 however, is carried by stationary shaft 77 having the laterally extending member 78, 100 while the apertured plate 76 is carried by the hopper. The hopper is provided with peripheral teeth 80 with which meshes an idler 81, the latter meshing with a circular rack 82 located above the producer. A poker 105 similar to that illustrated in Fig. 1 is shown at 83, the hollow shaft 84 of which carries a gear wheel 85, the latter meshing with the idler 86 which in turn meshes with the circular rack 82. The cover portion is driven 110 by means of the shaft 87 carrying a gear wheel 88 which meshes with peripheral teeth 90 formed upon the edge of the cover portion.

The operation of this embodiment of the 115 invention will be clear without further description.

It will be accordingly seen that I have provided apparatus well adapted to attain among others, all the objects and ends above 120 enumerated in a simple yet efficient manner; and as many changes could be made in the above construction and many apparently widely different embodiments of this invention could be made without departing from the scope thereof, it is intended that all matter contained in the above description or 125 shown in the accompanying drawings shall

be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having described my invention what I claim as new and desire to secure by Letters Patent is:

1. The combination of a gas producer having an axially revoluble cover portion, a fuel receptacle carried by the cover portion, an inclined revoluble poker carried by the cover portion, means for maintaining a water circulation in said poker, and means for revolving said poker on its axis during the revolution of said cover portion.

2. The combination of a gas producer having a revoluble cover portion, of a fuel receptacle and a poker mounted to revolve thereon, and a common means for driving said receptacle and poker.

3. The combination in a gas producer, of a body portion, a revoluble cover portion having a revoluble stirring member, and a revoluble fuel hopper mounted thereon.

4. The combination in a gas producer having fixed upper and lower body portions and a revoluble intermediate body portion, of a revoluble cover portion, a revoluble poker, and a revoluble fuel hopper carried by the cover.

5. The combination in a gas producer having a fixed upper and lower body portions and a revoluble intermediate body portion, of a revoluble cover portion, a revoluble poker, a revoluble fuel hopper carried by the cover, and a common means for driving said poker and hopper.

6. The combination of a gas producer having a revoluble cover portion, and an independent axially revoluble fuel hopper carried thereby.

7. The combination of a gas producer having a revoluble cover portion, an independent axially revoluble fuel receptacle carried by the cover portion, and axially revoluble means for agitating the fuel within said fuel receptacle.

8. The combination of a gas producer having a revoluble cover portion, an independent axially revoluble fuel receptacle carried thereby, and axially revoluble means within the fuel receptacle for stirring the fuel.

9. The combination of a gas producer having a revoluble cover portion, an independently revoluble poker depending from the cover portion within the producer, a fuel hopper upon the cover portion, said poker and said fuel hopper being independently revoluble.

10. The combination in a gas producer having fixed upper and lower body portions and a revoluble intermediate body portion, of a revoluble cover portion, a seal between said cover and the upper body portion, a revoluble poker carried by the cover portion, a revoluble fuel hopper carried by the cover portion, and means for revolving said poker and said fuel hopper during the revolution of said cover portion.

11. The combination in a gas producer having fixed upper and lower body portions and a revoluble intermediate body portion, of a revoluble cover portion, and means for revolving said intermediate body portion and said cover portion in opposite directions.

12. The combination in a gas producer having fixed upper and lower body portions, of a revoluble intermediate body portion and a revoluble cover portion, of means for revolving said intermediate body portion and said cover portion in opposite directions, a revoluble fuel receptacle carried by the cover portion, a revoluble poker carried thereby, and means for revolving said receptacle and said poker during the revolution of said cover portion.

13. The combination in a gas producer having fixed upper and lower body portions and an intermediate revoluble body portion, of a revoluble cover portion, means for sealing the points of jointure of the intermediate body portion and the adjoining body portions, means for sealing the point of jointure of the cover portion and the upper body portion, a revoluble poker carried by the cover portion, a revoluble fuel hopper carried thereby, a water seal provided upon the cover portion, means for revolving the intermediate body portion and the cover portion in opposite directions, and means for revolving the poker and the fuel receptacle during the revolution of the cover portion.

14. The combination of a gas producer divided into fixed and revoluble body portions whereby the fuel is agitated at the point of juncture of said body portions, a cover portion, a revoluble poker supported by the cover portion adapted to agitate the fuel in the upper part of the producer, a revoluble fuel hopper carried by the cover portion, and a common means for revolving the fuel hopper and the poker.

15. The combination of a gas producer divided into fixed and revoluble body portions whereby the fuel is agitated at the point of juncture of the two body portions, of a cover portion, a movably mounted poker mounted upon the cover portion and depending therefrom into the interior of the producer, said poker being adapted to agitate the fuel in the upper portion of the

producer, a fuel receptacle carried by the cover portion and means for revolving said fuel receptacle.

16. In combination, a gas producer having fixed and movable body portions whereby the fuel is agitated at the point of junction of the body portions, a cover portion, a revoluble poker supported by the cover portion and adapted to stir the fuel in the upper part of the producer, a revoluble fuel

hopper carried by the cover portion, means for revolving said poker, and means for simultaneously revolving the hopper.

In witness whereof I affix my signature in the presence of two witnesses.

JAMES A. HERRICK.
